UNITED STATES PATENT OFFICE.

EARL E. JOHNSON, OF CHICAGO, ILLINOIS.

PEN OR PENCIL NAME CLIP.

Application filed July 3, 1926. Serial No. 120,307.

My invention in general relates to a clip, and more particularly to a name clip, especially adapted for use in connection with pens and pencils.

I am aware that clips for pens and pencils are available at the present time which are adapted to have inserted therein a printed slip such as a small calendar insert. Such clips, however, are not very satisfactory due to the construction of their frame. Then too, it is difficult to replace the paper inserts in the frame of such a clip.

Also, the calendar clips as they are usually called, cannot be employed as a frame for a name plate, or the like, since they are not constructed for that purpose and are usually comparatively small in size.

I propose to provide a novel frame construction adapted to receive an insert such as a name plate, or the like, and once the insert is placed therein to retain the insert and to prevent it from falling out though the frame is turned upside down.

The novel frame construction of my invention is illustrated in the form of a clip particularly adapted for use in connection with pens and pencils. Several forms of this clip are illustrated in the accompanying drawing, but it is of course to be understood that the invention is not to be limited thereby, but only in so far as defined by the scope and spirit of the appended claims.

Furthermore, the entire clip construction of my invention is made of a single or unitary mechanical construction comprising essentially only a punching from a blank of metallic material which can be very economically manufactured, especially in large quantities.

Other objects and advantages of my invention will more fully appear from the following detailed description taken in connection with the accompanying drawings which illustrate several embodiments thereof, and in which:

Figure 1 is a front view of a clip embodying the features of my invention applied to a pencil;

Figure 2 is a rear view of the clip shown in Figure 1, the pencil being shown in dotted lines;

Figure 3 is a sectional view taken on substantially the line 3-3 of Fig. 1, illustrating the construction of the clip;

Figure 4 is a sectional view taken on the line 4-4 Figure 1, looking downwardly;

Figure 5 is a view of a modified form of clip in position on a pencil;

Figure 6 is a sectional view taken on the line 6-6 of Figure 7, looking downwardly;

Figure 7 is a view partly in section taken on the line 7-7 of Figure 5, looking in the direction indicated by the arrows;

Figure 8 is a front view of a modified form of clip applied to a fountain pen cap;

Figure 9 is a rear view of the clip shown in Figure 8, the fountain pen cap being illustrated in dotted lines;

Figure 10 is a sectional view taken on substantially the line 10-10 of Figure 8, looking in the direction indicated by the arrows;

Figure 11 is a sectional view taken on the line 11-11 of Figure 8, looking downwardly; and

Figure 12 is a view partly in section taken on the line 12-12 of Figure 8, looking in the direction indicated by the arrows.

Referring now to the drawings in detail, in which like reference numerals designate similar parts throughout the several views, 80 10 denotes generally a main frame portion adapted to co-operate with an article, such as a pencil 11. This main frame portion 10 is provided with a pair of side flaps or flanges 12 and 13, which are bent over the 85 main portion 10 to aid in defining a peripheral groove, indicated generally by the reference character 14. Associated with one end of the main portion 10 is an end flange or flap 15 which extends over the portion 90 10. This flap 15 is spaced from the ends of the two side flaps 12 and 13 forming a space or slot 16 through which an insert may be introduced into the frame, as will be described more in detail hereinafter.

The other end of the portion 10 is provided with a pair of opposite side flanges 17 and 18 which are spaced from the side flanges 12 and 13. Also, the end of the portion 10 adjacent the flanges 17 and 18 is 100 provided with an end flange or flap 19 which extends over the portion 10. This flap 19 is separated from the ends of the two side flaps 17 and 18 by means of a small space or slot 20. This slot 20 is adapted to serve a 105 similar purpose to that of the slot 16.

The portion 10 is provided with a pair of laterally extending ears or bands 22 and 23 positioned between the flaps or flanges 17 and 18 and the flanges 12 and 13. These 110 bands 22 and 23 are formed integral with the main portion 10 and are adapted to resilient-

ly grip the body of the pencil 11 for the purpose of securing the frame thereto. Each of these bands 22 and 23 is preferably arcuate in shape so as to enable it to fit around the periphery of the pencil. Of course, it is to be understood that although the pencil is illustrated as being hexagonal in cross section (Figure 4), it may be made of a circular or any other suitable shape without deviating from the features of my invention.

The portion 10 is also provided with a depressed portion 25 which is formed by slitting the portion 10 and depressing the portion intermediate the slits. This depressed portion 25 is adapted to co-operate with the pencil to grip an article such as a pocket flap, or the like. In other words, this portion 25 in reality constitutes a clip for the pencil. Thus it will be seen that the novel device which I have devised is a combination name plate and clip.

The frame is adapted to have introduced therein a transparent sheet 26 which may be made of any suitable material, such for example, as celluloid. This sheet serves as a protective covering for a name plate or card 27. Thus the plates 26 and 27 may be inserted into the peripheral groove 14 from either end of the frame through the means of the previously described slots 16 and 20. These slots 16 and 20 permit the cards to be inserted with facility in the frame. Also the flat flanges 15 and 19 serve to prevent the endwise displacement of the cards in the frame, even when the pencil is inverted.

The card 27, as shown in Figure 1, may be provided with any suitable data such, for example, as the name of the owner of the pencil. Also, this card may be used for advertising purposes if it is so desired.

In Figures 5, 6 and 7 I have illustrated a modified form of my invention. This form of the invention presents a much better appearance due to the construction of the frame. The face 30 of this frame is rectangular in shape and is provided with a rectangular opening 31. Formed integral with the face 30 are a plurality of side flaps 33, 34, 35 and 36. The pair of flaps 33 and 34 are separated by a space from the flaps 35 and 36 in much the same manner as are the flaps in the form illustrated in Figure 1. The face 30 is also provided with end flaps or flanges 38 and 39 which are spaced from the associated side flaps by means of openings or slots 41 and 42, respectively. Thus it will be seen that this form of my invention is substantially of an open construction and does not have a flat face, such as the face 10 in the construction shown in Figure 1.

Also the flanges or flaps in the construction shown in Figure 5 are positioned on the pencil side of the frame, or in other words on the side opposite to that of the flanges shown in Figure 1. This results in the

frame presenting a substantially flat appearance. The frame is adapted to accommodate insert cards 26' and 27', which are made of celluloid and paper, respectively. These inserts are introduced into the frame in the same manner as those inserted in the frame of the modification shown in Figure 1. The frame is also provided with a pair of arcuate shaped laterally extending band members 22' and 23' which serve to clamp the frame to the pencil 11.

In Figures 8, 9, 10, 11 and 12 I have illustrated a modification of my invention associated with a fountain pen cap 40. The cap 40 includes the usual type of clip 41". The frame or name plate shown in this form of the invention is substantially like that illustrated in Figure 5, with the exception that it is made somewhat larger in order to enable it to fit the pen properly. Also, by making the frame somewhat larger the cards inserted therein are adapted to have more information printed thereon. In Figure 8 I have illustrated the card 27" as having the name and address of the owner of the pen thereon. This insert may be protected by the usual celluloid or transparent plate 26" (Figure 11).

The frame includes a rectangular face portion 30' having a rectangular aperture 31' (Figure 11). Formed integral with the face 30' are a plurality of side flanges or flaps 33', 34', 35' and 36'. These flanges are positioned on the pencil side of the frame or name plate so as to cause the name flange to present a substantially flat appearance to the eye. The ends of the frame are provided with the usual ends of flanges 38' and 39' separated from the associated side flanges by means of slots or spaces 41' and 42' respectively. These slots 41' and 42' permit of the ready insertion of the cards in the frame. Furthermore, the frame has formed integral therewith a pair of arcuate shaped bands extending laterally therefrom and adapted to clamp the plate to the pen holder cap 40. I have designated these bands by the reference characters 22" and 23". As shown in Figure 10, the clip 41" extends downwardly over the ends of the two laterally extending bands.

From the foregoing it will be readily obvious that my device is not limited to pencils, but may be also used to advantage in connection with fountain pens. Moreover, although I have illustrated several forms of my invention, the invention is not to be limited thereby, but only in so far as defined by the spirit and scope of the appended claims.

I claim:—

1. As an article of manufacture, a frame including a peripheral slot adapted to receive an insert, said slot being defined by flaps turned back over the frame, the flap at one

- end of said frame being spaced from the associated side flaps so as to permit of the ready insertion of a card in the said frame, said end flap being adapted to prevent the 5 insert from falling from the frame when same is turned upside down, and lateral extensions formed integral with the side of the frame and adapted to secure said frame to an article such as a pencil.
- 10 2. As an article of manufacture, a frame including a peripheral groove adapted to receive an insert, said groove being defined by peripheral flanges turned back on portions of said frame, said flanges including 15 side and end flanges, the flange associated with one end of said frame being spaced from the ends of the associated side flanges to form a slot through which the insert may be readily introduced into the peripheral 20 groove, said end flange serving to prevent the insert from being displaced from the frame when the same is inverted and fastening means connected to the frame for enabling it to be fastened to an article such 25 as a rod or the like.
3. As an article of manufacture, a frame including a peripheral groove adapted to receive an insert, said groove being defined by peripheral flanges turned back on portions of said frame, said flanges including 30 side and end flanges, the flange associated with one end of said frame being spaced from the ends of the associated side flanges to form a slot through which the insert may be readily introduced into the peripheral 35 groove, said end flange serving to prevent the insert from being displaced from the frame when the same is inverted, and a pair of cooperating lateral ears extending from 40 the sides of the frame adapted to cooperate with the frame to secure the frame to an article such as a pencil.
4. As an article of manufacture, a frame including a peripheral groove adapted to receive an insert, said groove being defined 45 by peripheral flanges turned back on portions of said frame, said flanges including side and end flanges, the flange associated with one end of said frame being spaced from the 50 ends of the associated side flanges to form a slot through which the insert may be readily introduced into the peripheral groove, said end flange serving to prevent the insert from being displaced from the frame when the same is inverted, and means 55 formed integral with the frame for enabling it to be detachably fastened to a pencil, or the like, said frame having the flanges positioned on the pencil side so as to present 60 a substantially flat and smooth appearance.
5. As an article of manufacture, a frame including a peripheral groove adapted to receive an insert, said groove being defined by peripheral flanges turned back on portions of said frame, said flanges including side and end flanges, the flange associated with one end of said frame being spaced from the ends of the associated side flanges to form a slot through which the insert may be readily introduced into the peripheral groove, said end flange serving to prevent the insert from being displaced from the frame when the same is inverted, means formed integral with the frame for enabling it to be detachably fastened to a pencil, or the like, and a projection formed integral with the frame for cooperating with the article to enable it to be fastened to something else, such as a pocket flap or the like.
6. As an article of manufacture, a frame for carrying cards having means for enabling it to be detachably fastened to a pencil, or the like, and a projection formed within the dimensions of the frame for co-operating with the article and to enable it to be fastened to something else, such as a pocket flap, or the like.
7. As an article of manufacture, an insert carrying member having band portions formed integral therewith for enabling it to be detachably fastened to a pencil, or the like, and a depressed portion punched from said member adapted to cooperate with the article to enable it to be fastened to something else, such as a pocket flap, or the like, said member having a slot for enabling an insert to be readily introduced therein and including means for preventing the displacement of the insert in the member when the same is inverted.
8. As an article of manufacture, a frame comprising a single metallic punching and including a peripheral groove adapted to receive an insert, said groove being defined by peripheral flanges turned back on portions of said frame, said flanges being integral with said frame and including side and end flanges, the flange associated with one end of said frame being spaced from the ends of the associated side flanges to form a slot through which an insert may be readily introduced into the peripheral groove, said end flange serving to prevent the insert from being displaced from the frame when the same is inverted, and curved band portions formed integral with the frame and flanges for enabling said frame to be detachably fastened to a pencil, or the like, said frame having the flanges positioned on the pencil side so as to present a substantially flat and smooth appearance.

In witness whereof, I hereunto subscribe my name this 28th day of June, 1926.

EARL R. JOHNSON.
